Primary Examiner — Omeed Agilee*Assistant Examiner* — Michael Hoffman(74) *Attorney, Agent, or Firm* — Vladimir Postnikov(57) **CLAIM**

The ornamental design for a breast pump part, as shown and described.

DESCRIPTION

FIG. 1 is a front elevation view of a breast pump part showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is a perspective view thereof.

The broken lines in the drawings depict portions of the breast pump part that form no part of the claimed design.
